TOILET TANK CABINET

Kenneth C. Baker and Grace M. Baker,
San Jose, Calif.

Application September 26, 1949, Serial No. 5,172

Term of patent 14 years

(Cl. D4—5)

To all whom it may concern:

Be it known that we, Kenneth C. Baker and Grace M. Baker, both citizens of the United States of America, and both residing at San Jose, in the county of Santa Clara and State of California, have invented a new, original, and ornamental Design for a Toilet Tank Cabinet, of which the following is a specification, reference being made to the accompanying drawings, forming a part thereof.

Fig. 1 is a front elevational view of a toilet tank cabinet showing our new design;

Fig. 2 is a similar view thereof with the door open, exposing the inner rotatable containers;

Fig. 3 is an end elevational view looking from the right of the drawing, the supporting rod being fragmentarily shown for convenience of illustration;

Fig. 4 is a top plan view of Fig. 1, and
Fig. 5 is a cross-sectional view taken on the
line 5—5 of Fig. 1.

We claim:

The ornamental design for a toilet tank cabinet, substantially as shown.

KENNETH C. BAKER.
GRACE M. BAKER.
